UNITED STATES PATENT OFFICE.

ERD V. CROWELL, OF LOS ANGELES, CALIFORNIA.

TUBING ANCHOR.

Original application filed May 18, 1925, Serial No. 31,018. Divided and this application filed December 4, 1926. Serial No. 152,564.

This invention relates to tubing anchors, the present application being a division of my copending application Ser. No. 31,018, filed May 18, 1925; and it is the object of this 5 invention to provide for movement of a string of well tubing relative to its anchoring means when the latter is locked in a well casing, with said relative movement cushioned and finally limited to anchor the tubing without shock or 10 jar.

It is a further object of the invention to provide a cushioned tubing anchor which is adapted for automatic operation in the event of sudden dropping of the tubing during its withdrawal from a well bore, and which is also manually operative under control of the tubing and at the will of the operator as the tubing is being lowered in a well bore.

It is a still further object of the invention
20 to operate a tubing anchor by movement of a
string of tubing relative to a locking means
adapted to be frictionally held in a well cas-
ing, the frictional retaining means being ar-
ranged for ready yielding until such time as
25 it is desired to operate the anchor.

It is a still further object of the invention to construct the frictional retaining means so that it will hold the parts in position to prevent accidental operation of the anchor as the tubing is lowered in a well, and will tend to retain the parts in position for automatic operation of the anchor in the event of the tubing breaking during its elevation from the well.

35 Further objects of the invention will be readily understood from the following description of the accompanying drawings, in which:

Fig. 1 is a side elevation, partly in axial section, showing the improved tubing anchor in inoperative position.

Fig. 2 is a similar view showing the tubing anchor in operative position.
Figs. 3, 4, 5 and 6 are transverse sections on

45 the lines indicated in Fig. 1.
A usual string of casing 1 extends into the

well bore 2, and a string of tubing 3 is adapted for reception in the casing in spaced relation from its wall. One section 4 of the string of tubing is connected by coupling collars 5 to the ends of next adjacent lengths of the string 3; and a sleeve 7 is slidable on pipe section 4, and forms an abutment at its upper end, with a spring 11 coiled on the pipe section 55 between said abutment and the upper cou-

pling collar 5, in order to normally shift the sleeve downwardly relative to the pipe as shown in Fig. 1. Said downward movement of the sleeve is limited by abutment of its lower end against a shoulder 12 on the 60 pipe 4.

Sleeve 7 is adapted to be fixed against axial displacement in the well casing, and for this purpose a slip support 13 is slidably mounted on pipe 4 below sleeve 7 and preferably comprises sleeves 13^a and 13^b having axially extending cooperating tongues and recesses 14 at their adjacent ends, so as to permit relative axial movement of the sleeves and dependent rotation thereof relative to pipe 4. 70

Spring arms 14^a extend upwardly from lower sleeve 13^a through guide loops 15 on sleeve 13^b, and slips 16 carried by the arms are adapted to be expanded by sleeve 7 so as to engage the wall of casing 1 and thereby lock the sleeve against axial movement. For this purpose the lower end of sleeve 7 tapers downwardly to form a wedge 17 which slides down in back of the slips for expanding the same when pipe 4 and sleeve 7 are lowered relative to the slip support 13. 75 80

As the string of tubing is lowered in the well it is held against such axial movement relative to the slip support in order to prevent locking engagement of the slips, but when the string of tubing is at the desired level it is released from the slip support which is frictionally held in casing 1, so that further lowering of the tubing will shift the wedge 17 relative to the slips in order to engage the same in the casing and thereby lock sleeve 7 against axial movement. 85 90

The means for releasably holding pipe 4 relative to the slip support is shown as comprising gudgeons 18 on the pipe adapted to be received in slots 20 extending circumferentially of sleeve 13* with one end of the slots opening downwardly through the lower end of the sleeve as shown at 21. 95

While the string of tubing is being lowered, 100 pipe 4 is turned relative to the slip support so that the gudgeons 18 are locked in slots 20 as shown in Fig. 1, thereby preventing relative axial movement between the pipe and the slip support; and when the tubing is in place 105 the pipe 4 is turned until the gudgeons are in axial alignment with slots 21, to permit lowering of the string of tubing relative to the slip support as shown in Fig. 2.

The means for frictionally holding the slip 110

- support in casing 1 during such turning and lowering of the pipe 4 relative thereto, comprises outwardly bowed springs 22 permanently fixed at their respective ends to the sleeve 13, the springs 22 being frictionally engaging the wall of the well bore to limit the relative axial play of the tubing 4. The sleeve 13a and 13b permits movement of the springs for free adjustment to frictionally engage the wall of the casing.
- 10 When it is desired to anchor the tubing it is turned until the gudgeons 18 are in alignment with slots 21, the slip support being held against turning by its springs 22, and the tubing is then lowered with respect to the sleeve 7.
- 15 the slip support held against axial displacement by its springs, until the wedge 17 has been moved down in back of the slips 16 so as to expand the latter into biting engagement with the casing wall. It is thus obvious that
- 20 through control of the tubing the anchoring means is rendered operative or inoperative.

The operative engagement of slips 16 locks the sleeve 7 against axial displacement, and downward movement of the string of tubing 4 is thus cushioned and finally limited by compression of spring 11, to anchor the string of tubing in the well casing.

When the string of tubing is to be withdrawn from the well, pipe 4 is first elevated through the fixed sleeve 7 and then elevates the sleeve with the string of tubing by abutment of shoulder 12 against the lower end of wedge 17. The locking engagement of slips 16 is thus released so that elevation of the string of tubing may be continued, the slip support 13 being carried upwardly with the string of tubing by the abutment of gudgeons 18 against the upper walls of slots 20.

During withdrawal of the string of tubing, the pipe 4 is not turned so as to move gudgeons 18 back in slots 20, the gudgeons remaining in alignment with the open ends 21 of the slots so that if the string of tubing breaks, the slip support will be frictionally held in the casing by springs 22, while pipe 4 drops freely through the slip support to expand the slips by the wedge 17 and thereby lock the sleeve 7 in the well casing. Continued downward movement of the string of tubing relative to the anchored sleeve, will then compress spring 11 so as to cushion and finally limit dropping of the tubing, thereby anchoring the tubing without shock or jar.

The springs 22 are spirally disposed on slip support 13 so that as the string of tubing is lowered in a well the frictional engagement of the springs with the casing wall will tend to turn the slip support so as to maintain gudgeons 18 in the rear ends of slots 20; and in similar manner the frictional engagement of the springs during withdrawal of the tubing will tend to turn the slip support so as to maintain gudgeons 18 in alignment with the open ends 21 of the slots.

65 The locking engagement between the string

of tubing and the slip support is thus assured during lowering of the string; and when the tubing is withdrawn the parts are held in position for automatically locking the tubing in the well in the event of the tubing breaking.

The tubing anchor is thus adapted for automatic operation in the event of the tubing dropping while being withdrawn from a well, and is also adapted for manual operation at any desired level as the tubing is lowered in a well, the anchoring means being cushioned to prevent sudden shock or jar.

I claim:

1. The combination of a string of tubing adapted for reception in a well bore, sleeves on the tubing having cooperating longitudinal tongues and grooves whereby the sleeves are adapted for relative axial movement and dependent rotary movement on the tubing, springs fixed at their ends to the respective sleeves and adapted to frictionally engage the wall of the well bore or yield from said frictional engagement by relative axial movement between the sleeves, and means for anchoring the tubing in the well bore, said anchoring means being operated by relative movement between the tubing and the frictionally held sleeves.

2. The combination of a string of tubing adapted for reception in a well bore, sleeves on the tubing having a cooperating longitudinal tongue and groove whereby the sleeves are adapted for relative axial movement and dependent rotary movement on the tubing, springs fixed at their ends to the respective sleeves and adapted to frictionally engage the wall of the well bore or yield from said frictional engagement by relative axial movement between the sleeves, means for anchoring the tubing in the well bore, said anchoring means being operated by relative movement between the tubing and the frictionally held sleeves, and a locking connection between the tubing and one of the sleeves adapted for release by turning of the tubing relative to the frictionally held sleeves.

3. In combination, well tubing, a slip support on the well tubing comprising sections adapted for relative axial movement but dependent rotary movement, friction springs fixed at their respective ends to the respective sections of the support and adapted to engage the wall of a well bore, slips carried by one of said sections, and means on the tubing for expanding the slips to engage the wall of the well bore by relative movement between the tubing and slip support.

4. In combination, well tubing, a slip support on the well tubing comprising sections adapted for relative axial movement but dependent rotary movement, friction springs fixed at their respective ends to the respective sections of the support and adapted to engage the wall of a well bore, said springs being

spirally disposed relative to the support, slips carried by one of the sections, means on the tubing for expanding the slips to engage the wall of the well bore by relative movement 5 between the tubing and slip support, and means for locking the tubing and slip support against said relative movement or releasing said parts for said relative movement by reverse relative turning of the tubing and slip 10 support.

5. In combination, well tubing, a slip support on the well tubing comprising sections adapted for relative axial movement but de-

pendent rotary movement, friction springs fixed at their respective ends to the respective 15 sections of the support and adapted to engage the wall of a well bore, slips carried by one of the sections and guided by the other section, and means on the tubing for expanding the slips to engage the wall of the well bore 20 by relative movement between the tubing and slip support.

In testimony whereof I have affixed my signature.

ERD V. CROWELL.
